UNITED STATES PATENT OFFICE.

BURT A. MONTGOMERY, SIDNEY SMITH, AND EDWARD VON GUNTEM, OF AKRON, OHIO.

WINDOW-SCREEN.

1,177,434.

Specification of Letters Patent. Patented Mar. 28, 1916.

Application filed June 28, 1915. Serial No. 36,752.

To all whom it may concern:

Be it known that we, BURT A. MONTGOMERY, SIDNEY SMITH, and EDWARD VON GUNTEM, citizens of the United States, residing at Akron, in the county of Summit and State of Ohio, have invented certain new and useful Improvements in Window Screens; and we do declare the following to be a full, clear, and exact description of the invention, such as will enable others skilled in the art to which it appertains to make and use the same.

This invention relates to improvements in window screens and more particularly to those of the class which are connected to the window sash to open and close therewith.

The object of the invention is to provide a simply constructed and efficient screen of this character which will automatically wind up on the closing of the window and may be readily connected or disconnected from the sash.

Another object is to so construct a screen of this character that it may be engaged and supported by its inclosing casing when disengaged from the sash ready for connection with the sash when desired.

With the above and other objects in view, the invention consists of certain novel features of construction, combination and arrangement of parts hereinafter more fully described and claimed.

In the accompanying drawings: Figure 1 represents a front elevation of a window equipped with this improved screen shown attached to the sash and in a partially raised position; Fig. 2 is a longitudinal section taken on the line 2—2 of Fig. 1; Fig. 3 is a detail perspective view of one of the screen guides which is designed to be attached. Fig. 4 is a similar view of the bottom plate of the screen inclosing casing; Fig. 5 is a similar view of the casing cover; Fig. 6 is a similar view of the means which is carried by the upper end of the screen for connecting it either with the window sash or with its casing; Fig. 7 is a similar view of the screen attaching member carried by the window sash.

In the embodiment illustrated, a window frame F of ordinary construction is shown having secured to the inner faces of the opposite side members thereof screen guides 1 and 2 which are similar in construction and hence one only will be described in detail. Each of these guides is here shown formed

from a single plate of metal folded longitudinally upon itself intermediately of its width to form a laterally projecting rib 3 and which is provided on one edge with a flange 4 spaced from and arranged parallel with the rib 3 to form a groove 5 to receive and guide the screen proper to be described. At the other side of the rib 3 the plate extends at right angles to said rib and is apertured at longitudinally spaced intervals to provide an attaching flange 7 for connecting it to the frame. An extension 6 is formed on the lower end of each guide and is in the form of a continuation of the flange 4 and the spacer 4' which is arranged between said flange and the rib 3. This extension 6 is designed to form a stop for the screen to be described should it become accidentally disengaged from its casing or the sash and thus prevent said screen from swinging out of the window. It is of course understood that one of these stops is provided at each side of the window frame as is shown clearly in Fig. 1.

Secured to the window sill S is a screen casing here shown constructed of a base plate 8 which extends across the entire width of the window and is provided at its opposite ends with upstanding bearing plates 9 which are designed to receive the pintles of the screen roller 10, said roller being in the form of an ordinary window shade roller having a round pintle at one end for engaging a round aperture 11 in one bearing member and a square pintle at the opposite end, not shown, for engaging a square aperture 12 in the other bearing plate 9. This base plate 8 is provided at its rear edge with an upstanding flange 13 having cut out portions 14 at longitudinally spaced intervals and opposite said recesses or cut out portions 14 are laterally projecting apertured ears 15 for the passage of fastening elements for connecting the base plate to the window sill, said ears being here shown struck out of the flange 13. At the opposite edge of the base plate 8 are formed two pairs of hinge knuckles 16 which are designed to receive cooperating knuckles 17 carried by the casing cover 18, said knuckles being connected by the usual pintles not shown. This casing cover 18 is here shown semi-cylindrical in cross section with its free edge provided with an upturned flange 19 for a purpose to be described. Inwardly extending right angular lugs 20 are formed at opposite ends

of the casing cover 18 and apertured to adapt them to be connected to the bearing plates 9 at the opposite ends of the base plate 8, said bearing plates being provided with 5 apertures 21 arranged to register with the apertures in the lugs 20 when the casing cover is in closed position.

Secured to the inner face of the lower rail R of the lower window sash s is a screen 10 attaching plate 22 here shown in the form of a metal strip having an outstruck lip 23 which is designed for engagement by the screen to be described. This plate 22 is attached to the rail R by any suitable means 15 and extends substantially across the entire width of the sash, the lip 23 being offset from the sash a sufficient distance to provide for the insertion between it and the sash of the coöperating screen member to be described.

A strip of flexible screen fabric 25 is secured at one end to the spring roller 10 and a reinforcing and attaching member 26 is fastened to the free end of said screen fabric and is of a length corresponding to the width of the screen and to the distance between the side members of the frame, the ends of said member being designed to travel in the grooves 5 formed in the guides 1 which are secured to the side rails of the frame. This attaching member 26 which is shown in detail in Fig. 6, is constructed from a metal plate folded longitudinally midway its ends with the side members 27 and 28 thereof spaced apart a sufficient distance to receive between them the free end of the screen fabric which is secured thereto by clamping, riveting or in any other suitable manner. This plate is then 40 folded upwardly against the outer faces of the members 27 and 28 and arranged in close proximity thereto as shown in Figs. 2 and 6 and the edges of these upbent members 29 and 30 are bent downwardly and spaced 45 from said members 29 and 30 to form attaching hook-like flanges 31 and 32, said flanges being here shown terminating at their opposite ends at points spaced from the ends of the folded members to provide 50 ample space between them as the ends of said members are designed to slide in the grooves 5 when it is desirable that the attaching flanges should not interfere with this sliding movement. The hook-shaped 55 flange 32 which is disposed on the inner face of the screen is designed to hook over and engage the upstanding flange 19 on the casing cover 18 when the screen is detached from the sash to prevent this end of the 60 screen from winding up within the casing and to adapt it to be readily accessible for use when desired. The flange 31 which is disposed at the other side of the member 26 is designed to hook over and engage the lip 65 23 of the plate 22 which is attached to the

sash s and thereby reliably connect the screen with the sash to adapt it to be raised and lowered on the raising and lowering of the sash.

From an inspection of Figs. 1 and 2, it will be obvious that the rib 3 terminates above the casing 18 so that when the flange 32 on the screen is engaged with the flange 19 on the casing, the ends of the member 26 will be disconnected from the guides 1 and 75 be thus disposed out of the path of the window sash permitting it to be raised and lowered freely. The plate 22 carrying the attaching lip 23 is so disposed that when the member 26 on the free end of the screen is 80 engaged with said plate, the ends of said member will be arranged at the lower ends and within the grooves 5 of the guides 1 so that when the sash is raised, the screen will move upwardly with these ends traveling 85 in said grooves and thus prevent all possibility of lateral movement of the screen relative to the frame.

An upstanding hook 33 rises from the member 26 preferably at a point midway the ends thereof and is designed as a handle to facilitate the engagement and disengagement of the screen either with the casing flange 19 or with the sash plate 22 as may be desired.

From the above description, it will be obvious that this screen when not in use is completely coiled within the casing secured to the window sill S and is protected against dust and the like and when desired for use, it may be quickly connected with the sash by simply lifting the screen by means of the hook 33 and engaging the flange 31 thereof with the lip 23 on the sash s and the device is ready to be raised and lowered on the raising and lowering of said sash, it of course being understood that the spring roller performs the winding up function of the screen on the lowering of the sash in a manner similar to a shade roller.

We claim as our invention:

1. The combination with a window frame, a casing secured to the window sill inside the frame, a spring roller mounted in said casing, a screen fabric attached at one end to said roller, said casing having an opening for the passage of the free end of said screen and provided with an upstanding flange arranged adjacent said opening, a reinforcing strip clamped to the free end of said screen fabric and having downturned hook-like flanges on opposite sides thereof, one of said flanges being positioned to engage the upstanding flange on said casing when the screen is in one position, and a sash movable in said frame and having an offset lip for engagement by the other hook-shaped flange of said reinforcing screen strip when the screen is in another position.

2. The combination with a window frame

having guides secured to the opposite side members thereof and provided with longitudinally extending grooves, a sash mounted to move vertically in said frame, a plate secured to the lower rail of said sash and having a laterally offset upstanding flange, a spring roller mounted on the window sill adjacent the window opening, a casing enclosing said roller and having an upstanding flange, a strip of screen fabric secured at one end to said roller, a reinforcing and attaching member secured to the other end of said screen fabric with its ends positioned to engage the grooves of said guides, and hook-shaped members carried by said strip and positioned for engagement at the will of the operator with either the flange on the window sash or the flange on said casing.

3. The combination with a window frame, a base plate secured to the sill of said frame and extending transversely across the window at the inner side thereof, upstanding plates at the ends of said base plate, a spring roller mounted in said upstanding plates, a hood hingedly connected with one edge of said base plate and having an upstanding flange on its free edge, means for connecting said hood to said upstanding plates, a strip of screen fabric secured at one end to said roller with its other end free and adapted to pass out of said casing adjacent the flange on the hood thereof, a reinforcing strip attached to said free screen end having a hook for engaging the flange of the hood at the will of the operator, and coöoperating elements on said sash and reinforcing strip for detachably connecting the screen with said sash.

4. The combination with a window frame having a sash slidable vertically therein, of an offset flange extending transversely of said sash, a spring roller mounted on said frame, a screen attached at one end to said

roller, a reinforcing and attaching member secured to the free end of said screen and comprising a metal strip folded longitudinally intermediately of its ends to provide side members spaced apart to receive the screen, said strip being folded longitudinally and outwardly close against the outer faces of said side members and provided on one edge with a downturned hook-like flange for engagement with the flange on said sash.

5. The combination with a window frame having a sash slidable vertically therein, of an offset flange extending transversely of said sash, a spring roller mounted on said frame, a screen attached at one end to said roller, a reinforcing and attaching member secured to the free end of said screen and comprising a metal strip folded longitudinally intermediately of its ends to provide side members spaced apart to receive the screen, said strip being folded longitudinally and outwardly close against the outer faces of said side members and provided on its edges with downturned hook-like flanges, the ends of said flanges terminating short of the ends of the strip, and an upstanding hook-shaped handle carried by said strip, and means on said frame for engagement by one of said hook-like flanges to limit the lowering movement of the screen, the other hook-like flange being adapted to detachably engage the offset flange of the sash.

In testimony whereof we have hereunto set our hands in presence of two subscribing witnesses.
